UNITED STATES PATENT OFFICE.

CHARLES B. SCHOENMEHL, OF WATERBURY, CONNECTICUT.

PRIMARY BATTERY.

1,092,600.

Specification of Letters Patent. Patented Apr. 7, 1914.

Application filed December 9, 1910. Serial No. 596,396.

To all whom it may concern:

Be it known that I, CHARLES B. SCHOENMEHL, a citizen of the United States, and resident of Waterbury, in the county of New Haven and State of Connecticut, have invented certain new and useful Improvements in Primary Batteries, of which the following is a specification.

This invention relates to improvements in primary batteries of the class employed for railway signals and similar work, and including an assembled positive and negative electrode suspended in a suitable caustic or alkali solution, and more particularly of the type employing copper oxid as a negative electrode and zinc as the positive electrode.

It is the purpose of my invention to provide novel means for suspending the above class of assembled elements from the top of the jar irrespective of whether a cover be employed or not; to provide a construction which is equally adapted for both the compressed copper oxid plate and the loose copper scale when contained within a cylindrical basket and used in connection with a suitable form of zinc element; further to provide a novel form of suspension which will permit the assembled elements to be readily placed in or removed from the jar without disconnecting the said elements or operating any nuts or screws as has heretofore been necessary when such elements were suspended from the cover, and finally to so arrange and construct the suspending means as to dispense with the use of the cover, and thereby saving the cost of such cover.

My invention consists further in the details of construction and combination of parts hereinafter more fully described and claimed.

In the accompanying drawings forming a part of this specification Figure 1, shows a side elevation of an assembled cylindrical basket and zinc form of element suitably suspended within a jar by my improved form of suspending means. Fig. 2, is a plan view of the construction shown in Fig. 1. Fig. 3, is a similar side elevation of a popular style of compressed copper oxid plate and zinc plate form of assembled elements suspended within a battery jar and illustrating my improved suspending means as applied to that form of assembled element. Fig. 4, is a detached side elevation of the

assembled element shown in Fig. 3 and Fig. 5, shows my invention applied to still another form of holding frame, carrying a compressed copper oxid plate and zinc plates, forming the electrodes.

Referring in detail to the characters of reference marked upon the drawings 10 indicates an ordinary porcelain containing jar of suitable dimensions and designed to hold 65 the exciting fluid, and in which the assembled element is suspended.

The character 11 represents a cylindrical form of perforated basket as shown in Figs. 1 and 2, for containing oxid of copper scale 70 to form the negative electrode. This basket may be of any preferred construction and as shown includes two vertically disposed rods 12-12 for retaining the end caps of the basket in place, and for supporting the basket in position. A pair of insulating blocks 13 and 14 are also mounted upon the upper end portion of these two rods and serves to insulatively support a cross yoke 15 from the said rods. A cylindrical zinc element 16 is 80 hung from the two outer end portions of this yoke in a way to encircle the basket and to form the coating positive electrode. A field wire 17 is detachably connected to this element by means of a nut 18 secured to one of the hanger rods 19 as is clearly shown in Fig. 1. A second positive element 20 in the form of a zinc rod is connected with the cross yoke 15 and is suspended centrally within the negative basket so as to insure an action 90 on both sides of the cylindrical negative electrode, to increase the efficiency of the battery. The suspending means as applied to this assembled element consist of a metal strip 21, the intermediate portion of which 95 is secured to the top face of the insulating block 13 by means of the rods 12 passing through the said yoke and is provided with nuts 22 for clamping the strip 12 to the block. The outer end portions of the strips are deflected upward and have their extreme ends turned down to form a hook 23 to engage 100 the top edge of the jar from which the assembled element is suspended. This suspending strip, through the medium of the rods 12, is connected to the negative element and is provided with a binding screw 24 for the attachment of a second field wire 25. This form of assembled cylindrical element is designed to be hung from the cover of a 110 jar by a single suspending rod 25a as suggested by dotted lines in Fig. 1, and there-

fore it is practical to suspend this element which may have been previously hung from the cover by a single rod, by my strip and from the top edge of the jar as shown in the drawings.

In Figs. 3, 4, and 5, I have illustrated my invention as applied to plate forms of assembled elements, and wherein 11^a indicates the negative plate electrode and 16^a the positive zinc plate electrode. A smaller metal frame is secured to the edge portions of this negative plate, and as shown in Figs. 3 and 4 includes an inverted V shaped wire 26 for engaging the side and edge portion of the plate and sheet metal channel cross piece 27 for engaging the lower edge of the plate. A loop 26^b is formed in the top cross portion of the wire to cover an insulating block 28. A bolt 29 is passed through said insulating block for the attachment of the zinc or positive plates 16^b which are arranged on either side of the negative plate and at an equal distance therefrom. The field wire 17 is secured to the bolt 29 to form the electrical connection with the positive plates. In this form of construction I elect to form the suspending means in two parts 21^a, which, as shown in Figs. 3 and 4, comprise two sheet metal strips that are punched at 21^b to allow the wire side portions of the frame to be passed therethrough. The lower portions of these strips are seated against the respective side edges of the negative plate and beneath the wire side portions of the frame, so as to insure a good mechanical and electrical connection. The upper part of these side strips like that in the other forms are turned down to form hooks to engage the top edge of the jar.

The construction shown in Fig. 5, includes a popular form of plate holder made largely of channel sheet metal and including side channel pieces 21^a connected top and bottom with cross members 26^a and 27^a. The side

pieces 21^a have their edges disposed back 45 against the side of the plate to hold the same and strengthen the strip. The upper end portions of these strips like those on the other forms, are disposed out and turned down to engage the top edge of the jar. I 50 further provide an insulating covering 30 for the hook ends 23 of the hanger so as to prevent the batteries from becoming short circuited, when set up in series, should these hook portions happen to be placed one 55 against the other.

The foregoing construction enables me to suspend most any of the popular forms of assembled elements, from the top edge of a battery jar and central therein in a manner 60 to permit of them being readily inserted and removed as occasion may require and without the use of a cover, or bridge.

Having thus described my invention what I claim and desire to secure by Letters Pat- 65 ent is—

In a primary battery of the class described, the combination with an assembled element including positive and negative electrodes insulatively connected together and 70 carried by a single holding frame, of means for suspending the said elements with a battery jar and below the top thereof, comprising longitudinally disposed side strips secured to and forming a part of the frame 75 and having upwardly and outwardly disposed hangers the ends of which are disposed down to engage the top edge of a battery jar and to prevent lateral movement of the element within the jar, and a binding 80 screw attached to one of said ends.

Signed at Bridgeport in the county of Fairfield and State of Connecticut this 7th day of December A. D., 1910.

CHARLES B. SCHÖENMEHL.
